[57] CLAIM

The ornamental design for a "lock assembly housing", as shown and described.

DESCRIPTION

FIG. 1 is a top plan view of a lock assembly housing showing our new design;

FIG. 2 is a front elevational view thereof;

FIG. 3 is a right side elevational view thereof;

FIG. 4 is a bottom plan view thereof;

FIG. 5 is a rear elevational view thereof; and,

FIG. 6 is a left side elevational view thereof.

The broken-line disclosure in the views is for illustrative purposes only and forms no part of the claimed design.
